UNITED STATES PATENT OFFICE.

OLTMANN G. SCHMIDT, OF FARGO, NORTH DAKOTA.

GASOLINE TORCH.

Application filed June 4, 1926. Serial No. 113,715.

This invention relates to a gasoline torch and it consists in the novel features herein-after described and claimed.

An object of the invention is to provide a combination melting pot and babbitt ladle and gasoline vapor torch with which the babbitt can be melted and poured while the flame is under the bowl of the ladle and while the metal is being poured. If desired the ladle may be removed from the torch.

With these and other objects in view the torch comprises a body having a head portion and a shank portion and with a handle grip attached to the shank portion. The head of the body is divided by a horizontal partition wall into upper and lower chambers and the shank and handle grip are provided with a passageway there being a valve provided upon the shank for controlling or regulating the movement of gasoline vapor through the passageway. The said passageway communicates at its inner end with the uppermost chamber in the head. A by-pass passageway connects at one end with the first mentioned passageway and with the lower chamber in the head. Burner nozzles are screw threaded in the partition wall of the head and their upper end portions passed through openings provided in the top of the head. The burner nozzles are provided with ducts which communicate at their lower ends with the interior of the lower compartment in the head and wicks are embedded in the upper side of the head and surround the burner nozzles. Means are provided for leading vaporized or carbureted air into the first mentioned passageways through the handle grip.

In the accompanying drawing:

Figure 1 is a top plan view showing a ladle mounted upon the gasoline torch;

Figure 2 is a longitudinal vertical sectional view of the torch;

Figure 3 is a transverse sectional view thereof cut on the line 3-3 of Figure 2;

Figure 4 is a fragmentary side elevational view with parts in section of the means for conducting the vapor and carbureted air to the torch.

As illustrated in the accompanying drawing, the ladle includes a bowl 1 having a handle 2 attached thereto. The body of the torch includes a head 3, a shank portion 4 having a handle grip 5 attached thereto.

The head 3 is hollow and is provided in its

interior with a horizontal partition wall which divides the interior of the head into chambers 7 and 8. A passageway 9 leads through the shank 4 and handle grip 5 and communicates at its inner end with the chamber 7. A valve 10 is turnably mounted in the shank 4 and is arranged to control the flow of vapor through the passageway 9. A by-pass passageway 11 connects at one end with the passageway 9 and at its other end communicates with the interior of the chamber 8.

Burner nozzles 12 pass through the upper and lower sides of the head 3 and are provided at points between their ends with screw threads 13 which are screwed into the partition wall 6. The upper end portions of the nozzles 12 are reduced in diameter and pass through relatively large openings 14 in the top wall of the head 3. Wicks 15, preferably of wire netting, are embedded in the upper portion of the top wall of the head 3 and surround the upper ends of the nozzles 12 and substantially fill the upper ends of the openings 14. The nozzles 12 are provided with ducts 16 which open at the upper ends of the said nozzle and the lower ends of the ducts 16 communicate with the interior of the chamber 8 in the head 3.

A nipple 17 is connected with the end of the handle grip 5 and communicates with the passageway 9. The means for supplying vaporized air to the torch consists of a compressed air tank 18 having a pressure gauge 19 mounted thereon and a pipe 20 connected with the top side thereof. The pipe 20 is provided with valves 21 and 22. One end of the pipe 20 enters a gasoline tank 23. A pipe 24 also communicates with the gasoline tank 23 and may be connected with the nipple 17. A by-pass pipe 25 connects the pipe 20 with the pipe 24 and is provided with a valve 26. Stand members 27 are connected with the intermediate portion of the shank 4 and are provided at their upper ends with shelf portions 28 in which the handle 2 of the ladle fits. Pins 29 may be provided for fixing the handle 2 of the ladle to the shelf portion 28 as best shown in Figures 2 and 3 of the drawing.

In use the parts are assembled as shown in Figure 2 of the drawing and the metal to be melted is placed in the bowl 1 of the ladle. When the valves 21 and 22 are open the air passes from the tank 18 through the

pipe 20 into the tank 23. The said air is carbureted in the tank 23 and the carbureted air passes through the pipe 24 and nipples 17 into the passageway 9 of the handle and shank of the torch. When the valve 10 is at an open position as shown in Figure 2 with relation to the passageway 9, the vapor or carbureted air passes from the passageway 9 into the compartment 7 and from the passageway 9 through the passageway 11 into the compartment 8 of the head of the torch. The vapor which enters the compartment 7 passes up through the openings 14 and through the wicks 15 and is ignited under the bowl 1 of the ladle. At the same time the vapor and carbureted air, which is admitted into the chamber 8 passes into the ducts 16 of the nozzle 12, thence up through the said ducts to the point of ignition immediately below the bowl 1 of the ladle. When the valve 10 is open the bowl of the ladle is subjected to a very hot flame. When the valve 10 is closed, the fuel is cut off from the upper chamber of the head of the torch and the flame is supplied by fuel which passes through the ducts 16 only and consequently the flame below the bowl of the ladle is not so hot.

When it is desired to pour the metal which has been melted in the bowl 1 of the ladle, the handle grip 5 is grasped while the handle of the ladle is retained in the shelf portions 28 of the stand 27. At the same time, the flame may be permitted to burn under the bowl of the ladle. Thus the ladle and the torch may be turned and the metal may be poured and in view of the fact that the flame remains in close proximity to the bowl of the ladle the metal will not have a chance to cool off during such time as it is being poured from the bowl of the ladle.

From the foregoing description, taken in conjunction with the accompanying drawing, it will be seen that the combination melting pot and gasoline vapor burner or torch of simple and durable structure is provided and that the same may be conveniently and economically used for melting and pouring metals.

Having described the invention what is claimed is:—

1. A gasoline vapor burner comprising a body having a head portion and a shank

portion, the head portion being hollow and having a horizontal partition wall which divides the interior thereof into upper and lower chambers, the shank portion having passageways which communicate one with the other and which communicate at their inner ends with the chambers respectively, a valve for controlling the passage of vapor through one of the passageways, and burner nozzles passing through the upper and lower walls of the head and engaging in the partition wall of the head the lower ends of the nozzles being closed, the upper ends of the burner nozzles being spaced from the surfaces of the walls of the upper side of the head, wicks surrounding the discharge ends of the burner nozzles, said nozzles having ducts which communicate at their lower end with the lower compartment of the head.

2. A gasoline torch comprising a head having a shank provided with a valve controlled passageway, the head being hollow and having an interiorly located horizontally disposed partition wall dividing the same into upper and lower compartments, burner nozzles passing through the upper and lower walls of the head and having screw thread engagement in the partition wall the lower ends of said nozzles being closed, said burner nozzles having ducts which communicate with the lower compartment of the head.

3. A gasoline torch comprising a head having a shank provided with passageways one of which is controlled by a valve, the head being hollow and having an interiorly located horizontally disposed partition wall dividing the same into upper and lower compartments, said partition wall being located between said passageways, burner nozzles passing through the upper and lower walls of the head and having screw thread engagement in the partition wall, the lower ends of said nozzles being closed, said burner nozzles having ducts which communicate with the lower compartment of the head.

In testimony whereof I affix my signature.

OLTmann G. SCHMIDT.
